DOORLATCH

Charles E. Dath, Chicago, Ill., assignor to W. H. Miner, Inc., Chicago, Ill., a corporation of Delaware

Application May 18, 1932, Serial No. 611,948

2 Claims. (Cl. 292—241)

This invention relates to improvements in door latches especially adapted for doors of refrigerator trucks or cold storage containers used in connection with container cars.

5 One object of the invention is to provide a latch for a hinged door adapted to either force the door open or tightly close the same, and also lock it in closed position, so designed that proper operation is ensured at all times regardless of 10 slight sagging of the door with respect to the door frame due to the weight of the door and unavoidable play in the hinge connection.

A more specific object of the invention is to provide a latch means for single doors of the 15 hinged type, including a lever operated crank member mounted on the door for rotation about a horizontal axis and having operative engagement with a keeper fixed to the door frame for forcing the door open or tightly closing the same, 20 wherein the keeper is provided with guide means engageable by a portion of the crank member to ensure proper registration of the keeper engaging means and keeper during operation of the device in closing the door.

25 A still further object of the invention is to provide in a door latch of the character described in the preceding paragraph means cooperating with the crank member to hold the same against movement to lock the door in closed position.

30 Other objects of the invention will more clearly appear from the description and claims herein-after following.

In the drawing, forming a part of this specification, Figure 1 is a side view of the wall of a 35 container, such as is used in connection with container cars, the wall being provided with a door opening, which is closed by a single door, said view illustrating my improved operating latch in connection therewith. Figure 2 is a view 40 similar to Figure 1, on an enlarged scale, certain parts shown in Figure 1 being broken away. Figure 3 is a vertical sectional view, corresponding substantially to the line 3—3 of Figure 2. And Figure 4 is a vertical sectional view, on an 45 enlarged scale, corresponding substantially to the line 4—4 of Figure 1.

In said drawing, 10 designates the side wall of a member, such as a container used in connection with container cars for railways, provided with 50 a door opening 11 closed by a single door indicated by 12. The door is of the swinging type and is supported by a pair of hinges 13—13 secured to the wall 10 at one side of the door opening.

55 My improved door latch comprises broadly a keeper A; a supporting bracket B; a lever oper-

ated keeper engaging crank member C; and a lock D.

The keeper A is in the form of a casting having a flange 14, by which it is fixed to the wall 10. The casting has an outstanding section 15 provided with an inclined slot 16, with which the crank member C cooperates. The section 15 is provided with a horizontal ledge or flange 17 at the bottom thereof, which is located on the side of the casting A nearest the door. At the outer 65 end, the ledge 17 is bevelled, as indicated at 18, thus providing an inclined section. As clearly shown in Figure 4, the ledge 17 is located beneath the slot 16 of the keeper.

The supporting bracket B comprises a flat 70 platelike section 19, which is secured to the outer side of the door adjacent to the free edge thereof, as clearly shown in Figures 1 and 2. The bracket B is provided with bearing means 20—20 for the crank C, said bearing means comprising a block 21 having spaced bearing projections 121—121 disposed in seats 22—22 provided by outstanding straplike portions 23—23 on the bracket B. The bearing projections 121—121 of the block 21 and the outer sections 80 of the straps 23—23 are provided with opposed curved bearing surfaces, which together form complete cylindrical bearing members. Each strap 23 is provided with a depending stop lug 24, for a purpose hereinafter pointed out. The 85 lugs 24—24 are in transverse alignment, as clearly shown in Figures 2 and 3.

The lever operated keeper engaging crank member C comprises a crank member proper 90 having a journal portion 26, which is rotatable within the bearing means 20 at the outer side of the bracket B. Formed integral with the crank member C is an operating lever 27, which has a bearing trunnion 28 at the outer side thereof in axial alignment with the journal portion 26 of the crank member proper. The operating lever 27 is disposed between the two bearing means 20—20 and has a web 29 adjacent to the inner end thereof, said web being provided with a transverse opening 30, which is so located as 95 to be disposed in back of the lugs 24—24 when the operating lever 27 is in the position shown in Figures 1, 2, and 3.

The lock D, which is employed to hold the 100 crank member against movement when the door is in closed position so as to lock the same, is preferably in the form of a padlock having the hasp thereof engaged through the opening 30 of the web 29 of the lever 27 so as to engage in back of the stop lugs 24—24. The portion of 105 110

the crank which engages within the slot 16 of the keeper is indicated by 31 and is preferably of cylindrical cross section, as shown in Figure 4. The keeper engaging portion 31 of the operating crank C is carried at the outer end of the crank arm 32. The inner end of said crank arm, where it joins the journal portion 26 of the crank C, is in the form of a curved flange 33, which is concentric to the journal portion 26, as clearly shown in Figure 4. The flange 33 forms a guide member, which cooperates with the guide ledge 17 of the keeper A to align the keeper engaging portion 31 of the crank C with the slot 16 of the keeper A during the operation of closing the door.

In forcing the door open, the operation of my improved latch is as follows: The lever 27 is swung outwardly and upwardly from the position shown in Figures 1, 2, and 3, thereby rotating the keeper engaging portion 31 of the crank C in a clockwise direction, as viewed in Figure 4. Rotation of the keeper engaging crank in this direction brings the engaging portion 31 thereof in contact with the rear wall of the slot 16 of the keeper A. Further rotation of the crank C will cam the door outwardly, thereby forcing the same open. The portion 31 of the crank clears the slot 16 of the keeper A when the lever 27 has been raised to the proper height, thereby permitting the attendant to swing the door to fully opened position.

When closing the door, the operating lever 27 is in raised position so that the keeper engaging portion 31 of the crank will be disposed below the entrance to the slot 16 of the keeper A. In swinging the door to closed position, the flange 33 of the crank arm of the crank C engages the inclined section 18 of the ledge 17, thereby bringing the engaging portion 31 of the crank into registration with the open end of the slot 16 of the keeper A. When the parts are thus positioned, the operator swings the lever 27 downwardly, thereby rotating the crank member C in a counterclockwise direction, as viewed in Figure 4, thus causing the keeper engaging portion 31 of the crank to enter the slot 16 and engage with the outer wall of the slot to cam the door inwardly and force the same tightly into the door opening. When the door has been tightly closed, the lever 27 is in the position shown in Figure 3. As will be evident, the operating crank C may then be locked by engaging the hasp of the padlock D through the opening 30 of the web 29 of the lever.

In heavy door constructions, such as are employed in connection with cold storage containers or refrigerator automobile trucks, it frequently

happens that the doors will sag slightly due to unavoidable looseness in the hinge connections thereof, thus preventing proper alignment of the keeper engaging means of the door operator and the slot of the keeper. As will be evident, my improvements overcome this defect by providing positive means for guiding the keeper engaging means so that the same will register with the slot of the keeper. Further, the rigid guide ledge on the keeper, which cooperates with the bearing means on the rotary keeper engaging crank member, which bearing means is concentric with the axis of rotation of the crank member, provides a simple and efficient mechanism for bringing the keeper engaging member into proper registration with the slot of the keeper.

I have herein shown and described what I now consider the preferred manner of carrying out my invention, but the same is merely illustrative and I contemplate all changes and modifications that come within the scope of the claims appended hereto.

I claim:

1. In a door latching mechanism for members having a wall provided with a door opening closed by a single door adapted to swing about a vertical axis, the combination with a slotted keeper fixed to said wall; of an operating member mounted on said door for rotation about a horizontal axis, said member having a keeper engaging portion adapted to engage within the slot of said keeper, said keeper engaging portion being eccentric to the axis of rotation of said member, said member also having a cylindrical bearing portion thereon concentric with the axis of rotation thereof; and a guide flange on said keeper adapted to be engaged by said bearing portion of said member to register the keeper engaging portion thereof with the slot of the keeper.

2. In a door latching mechanism for members having a wall provided with a door opening closed by a single door adapted to swing about a vertical axis, the combination with a slotted keeper fixed to said wall; of an operating member mounted on said door for rotation about a horizontal axis, said member having a keeper engaging portion eccentric to the axis of rotation thereof adapted to engage within the slot of said keeper, said member having an arcuate guide flange thereon concentric with the axis of rotation thereof; and a horizontal guide ledge on said keeper engageable by said guide flange and slidably supporting the same to register the offset eccentric keeper engaging portion of said member with said slot, said guide ledge having an inwardly inclined outer end section.

CHARLES E. DATH.
